UNITED STATES PATENT OFFICE

CARL WESSEL, OF ESSEN-BORBECK, GERMANY, ASSIGNOR TO THE FIRM CARL STILL, OF RECKLINGHAUSEN, GERMANY

METHOD OF HEATING COKE OVENS

Application filed January 30, 1928, Serial No. 250,664, and in Germany January 31, 1927.

The purpose of the invention is to provide and maintain uniform temperature conditions throughout coke oven chambers regardless of the height to which the latter may be built. To this end the invention consists in the provision of a heating system in which a small amount of highly heated air is mixed with the gases before the latter pass into the lower ends of a plurality of vertically disposed distributing pipes located within the heating flues of the coke oven. The distributing pipes are provided with discharge openings located at various heights and combustion supporting air is supplied to the flues in sufficient quantity to effect combustion at said openings. The air initially supplied to the gases serves to prevent decomposition of the gases prior to combustion at the openings through which the gases pass from the distributing pipes to the heating flues.

A coke oven embodying the principles of the invention is illustrated in the accompanying drawing in which:

Figure 1 is a vertical longitudinal section taken on the line A—B of Figure 2, and,

Figure 2 is a vertical cross-sectional view taken on the line C—D of Figure 1.

The heating-gas, required for heating, is supplied to the individual oven during the respective heating-period by the heating-gas conduit a , or a_1 and in heating the left hand half passes for instance by means of the connecting-pipes b or b_1 (Fig. 1) into the gas distributing-channels c and c_1 , respectively, disposed below each heating-wall half. It is there distributed through the different nozzles d , d_1 , of which one each has been provided for every heating-flue.

The required air for combustion is taken from the regenerators g and k provided below the coking-chamber f . The air coming from the regenerator g through the channels i , strikes in the mixing-chambers h first the gas-current coming from the nozzles d , where-by mixing and partial combustion are effected. The gases mixed with a partial volume of air, pass into the distributing-pipe l or l_1 , vertically arranged in every heating-flue and provided with lateral openings m . The gases escape through the openings m , m_1 at various

heights into the open space of the heating-flues, where a complete combustion up to the top of the heating-flues takes place gradually by means of air entering from the regenerator k through the ducts n into every heating-flue.

The waste heat gases produced during combustion in each heating-wall half, are collected in the usual way in the upper receiving-flues e , e_1 and in the cross-channel O .

I claim:

The method of uniformly heating the flues of a coke-oven by fuel gas subject to decomposition by heat, which comprises the steps of mixing the fuel gas preliminary to introduction into the flues with a quantity of highly heated air insufficient to support combustion, but sufficient to prevent decomposition under the influence of the surrounding heat, separately supplying to the flues secondary air sufficient with the amount in the mixture aforesaid to support combustion, and then conducting the mixture of gas and air first mentioned to various distributing points spaced lengthwise in the flues, whereby combustion is effected at the distributing points.

In testimony whereof I have affixed my signature.

CARL WESSEL.
